Design for a Carpet Pattern.

The schedule referred to in these Letters Patent is not making part of the same.

Wall whom it may concern:

Be it known that I, Edwin J. Key, of Lowell, in the County of Middlesex and State of Massachusetts, have originated and designed a new Pattern for carpets or other fabrics, of which the following is a full, clear and exact description, reference being had to the accompanying drawings, making part of this specification.

The letter A represents a group of leaves resting on a sprig work B, the whole being surrounded by the branches C.

D represents a large leaf resting between the branches and sprig work B.

The figure A forms a centre composed of leaves which are surrounded by scroll 2, and coral work 3, resting on the plain ground 4.

The remainder of the design is composed of leaves, branches, sprigs &c.

The colors employed in the different portions of the design, may be varied to suit the taste and wish of the manufacturer.

Claim.

What I claim as my invention and desire to secure by Letters Patent is The design or pattern for carpets or other fabrics, herein set forth.
